UNITED STATES PATENT OFFICE.

J. BENNETT WALLACE, OF CHICAGO, ILLINOIS, ASSIGNOR TO GEORGE M. CLARK & COMPANY, OF SAME PLACE.

GENERATING GASOLINE-BURNER.

SPECIFICATION forming part of Letters Patent No. 369,826, dated September 13, 1887.

Application filed March 21, 1887. Serial No. 231,647. (No model.)

To all whom it may concern:

Be it known that I, J. BENNETT WALLACE, a citizen of the United States, residing in Chicago, in the county of Cook and State of Illinois, have invented a new and useful Improvement in Generating Gasoline-Burners, of which the following is a specification.

This invention relates to improvements in the device for moving the deflecting tube whereby the vapor is deflected from the induction-tube of the generating-burners of gasoline-stoves to the under side of the burner base-plate, for the purpose of keeping the latter hot when the stove is not in use, and particularly to the form of such device employed with vertical deflectors and induction-tubes. These vertical deflectors are hinged at the top, and it has been customary to position them by means of wires some eight inches in length projecting to the front and rigidly attached to the deflectors, so that when the outer ends thereof are vibrated vertically the deflectors are caused to swing upon their hinges, thereby moving the lower end of the deflectors into acting position over the mouth of the needle-valve of the burner, or away therefrom, as desired, the deflector being held in position by frictional contact between it or the wire and a stationary surface located upon the valve or other convenient part of the burner. The deflector-wire, when made to project in this manner and having this vertical vibratory movement, is subject to some objections. It is peculiarly subject to gravity, owing to its length and the thumb-piece with which it is usually provided at its free end, and unless its friction device is fully operative it is liable to fall from its upper to its lower position when such change is not desired, and as the friction-surfaces are apt to wear away or become separated by bending, this liability to displacement through gravity is very considerable. The wire is also in such close proximity to the needle-valve stems of the other burners fed by the generating-burner as to render it liable to accidental displacement by the user when operating such valve-stems. Any lateral blow or force exerted upon the wire will also tend to separate the friction-surfaces, and thus render the device inoperative, except in one position—viz., the lower one.

My present invention is designed to remove these objections and to otherwise improve the method of positioning and holding the deflector.

55

It consists in the positioning and holding mechanism hereinafter specifically described and claimed.

In the accompanying drawings, which form a part of this specification, and in which similar letters of reference indicate like parts, Figure 1 is a side elevation of a generating-burner the deflector whereof is operated by my improvement. Fig. 2 is a plan of the same, the burner proper and its base being partly broken away. Figs. 3 and 4 are enlarged side views of the deflector and its immediate operating mechanism, showing the two positions thereof. Fig. 5 is a rear elevation of the parts shown in Figs. 3 and 4. Figs. 6 and 7 are vertical sections of the mixing-tube and deflector, the latter being shown in both positions.

In the drawings, A represents the burner proper, a the base-plate, B the mixing-tube, C the deflector-tube, (hinged at c,) and D the needle-valve, of a generating-burner, the valve being operated by the hand-wheel d. Associated with this burner are other needle-valves for regulating the other burners of the stove which are fed from the generating-burner shown, the stems of such other burners being indicated at E, and all projecting to the front of the stove in a horizontal plane.

The deflector-tube may form a portion of the mixing-tube, as explained in patent to me, No. 314,404, and it is moved into and out of position by turning the rotatable wire shaft F, journaled at f, upon the mixing-tube, and connected to the deflector by the crank G and pitman g. The friction for holding the deflector against accidental movement is obtained between the arm H upon the deflector and the stationary lug h upon the side of the valve-cylinder. With this operating device gravity upon the part of the operating-wire which is positively sustained in its bearings f is absolutely prevented from operating the deflector, and side or other pressure upon the operating-wire does not tend to separate the friction-surfaces, and it is not easily operated by accidental contact, as is the vibrating wire.

The wire F extends nearly at right angles

to the stems E of the needle-valves, so that the user is not likely to mistake it for either of said stems, and it is so far removed therefrom as to be safe from accidental contact with the hand 5 when actuating the needle-valves. It and the mechanical connections can also be connected to the deflector when positioned back of the induction-tube, as in the former construction, and without any change in the shape thereof 10 or in the location of the friction-surfaces.

I claim—

The swinging vertical deflector-tube of a generating gasoline - burner, in combination with the rotatable shaft, the crank and the pitman for moving said deflector, and the friction devices H and h, for holding it against accidental movement, substantially as specified. 15

J. BENNETT WALLACE.
